[57] CLAIM

The ornamental design for a belt adjuster, as shown and described.

DESCRIPTION

FIG. 1 is a front elevational view of a belt adjuster showing my new design;

FIG. 2 is a rear elevational view thereof;

FIG. 3 is a right side elevational view thereof, the left side being a mirror image;

FIG. 4 is a top plan view thereof, the bottom being a mirror image;

FIG. 5 is a sectional view taken along line 5—5 of FIG. 1;

FIG. 6 is a sectional view taken along line 6—6 of FIG. 1; and

FIG. 7 is a front and bottom isometric view thereof.

FIG. 2

FIG. 4

FIG. 1

FIG. 3

FIG. 5

FIG. 6

FIG. 7
